APPARATUS FOR HANDLING COILS

Edward A. Laine, Leechburg, Pa., assignor to Allegheny Ludlum Steel Corporation, Brackenridge, Pa., a corporation of Pennsylvania

Application August 25, 1955, Serial No. 530,463

12 Claims. (Cl. 100—14)

This invention relates to apparatus for handling slit strip coils of steel and the like for facilitating the banding thereof.

When steel such as stainless, the electrical silicon-iron, or the like, is rolled and finished in wide strip form, the strip is usually wound into coils. Thereafter the coils are slit to predetermined widths and a plurality of slit strip coils, usually of different widths, is obtained from a single coil. In shipping such slit strip coils it is desirable to band the individual coils to hold them compact and to prevent shifting of the convolutions thereof with accompanying damage to the edges of the strip and introduction of strains therein.

Because of the weight of the wound coil it has heretofore been difficult to handle the coil during the banding thereof without introducing strains into the strip and in particular into the electrical silicon-iron grade of steel. Considerable efforts have heretofore been expended in attempting to perfect an integrated handling and banding apparatus, but such attempts have not proven to be commercially successful because of the manual operations required, or where mechanized equipment has been produced and used it has been found that the coils are often damaged during the handling and banding operation.

An object of this invention is to provide apparatus for mechanically handling slit strip coils for facilitating the banding thereof.

Another object of this invention is to provide apparatus for supporting a coil during a movement thereof from a source of supply to a coil supporting position in a different plane without damaging the coil and to automatically free the coil from such coil moving apparatus when the coil is in such different plane.

Another object of this invention is to provide apparatus for supporting a coil during a movement thereof from a source of supply and to automatically deposit such coil on support members which can be indexed through a plurality of banding positions.

A further object of this invention is to provide, in apparatus for facilitating the banding of coils, a rotatable arm movable from a vertical coil receiving position to a horizontal coil freeing position, the rotatable arm being provided with a pivotally mounted coil shoe support and having means for automatically operating the coil shoe support when the arm is in the vertical position to engage the coil and support it on the arm during movement thereof and to release the coil when the arm is in the horizontal position to automatically deposit the coil on support members disposed for facilitating the banding of the coils.

A more specific object of this invention is to provide, in apparatus for facilitating the banding of coils, a supporting arm movable from a downwardly depending vertical position through a horizontal position to an upwardly extending vertical position to receive a coil from a source of supply, the supporting arm having pivotally mounted support means carried thereby automatically operated when the arm is in the upwardly extending vertical position to engage the coil and support the coil on the arm during movement thereof and to release the coil when the arm is in the horizontal position to automatically deposit the coil on support members which can be indexed through a number of banding positions when the arm is in the downwardly depending vertical position.

Other objects of this invention will become apparent from the following description when taken in conjunction with the accompanying drawings in which:

Fig. 1 is a view in side elevation of apparatus embodying features of this invention;

Fig. 2 is a schematic plan view illustrating a general plant layout of apparatus embodying this invention;

Fig. 3 is a view in elevation and greatly enlarged illustrating a portion of the apparatus of Fig. 1 in one of the operating positions;

Fig. 4 is a view in elevation of a portion of the apparatus of Fig. 3 in another of the operating positions;

Fig. 5 is a view in elevation of the apparatus of Fig. 4 in still another operating position;

Fig. 6 is a side view in elevation, greatly enlarged and with parts broken away, of a portion of the apparatus of Fig. 1;

Fig. 7 is a view in front elevation of the apparatus of Fig. 6;

Fig. 8 is a plan view in section of a representative multi-port control valve suitable for use in controlling the operation of the hydraulic cylinders represented in the apparatus of Figs. 3 through 7;

Fig. 9 is a top plan view of a portion of the indexing apparatus utilized in the general assembly of the apparatus of Fig. 1; and

Fig. 10 is a view in section of a portion of the indexing apparatus taken along the line X—X of Fig. 9.

Referring to the drawings and in particular to Fig. 1 thereof, this invention is illustrated by reference to the apparatus shown generally at 10 embodying features of this invention for facilitating the handling and banding of slit strip coils 12. The general assembly 10 of the apparatus embodies a number of different pieces of equipment disposed to cooperate to efficiently handle a slit strip coil 12 for moving it from a source of supply, in this case, represented by a suitable turnstile assembly 14, to a position where the slit strip coil 12 can be efficiently and successfully banded. Thus the general assembly 10 of apparatus comprises the turnstile assembly 14 carrying a supply of the slit strip coils 12, a coil handling and moving apparatus shown generally at 16 disposed adjacent the turnstile 14 and disposed to be operated for depositing a slit strip coil 12 on a suitable coil support shown generally at 18, which coil support 18 can be suitably indexed through a number of banding positions. A banding machine, represented by the rectangle 20, is disposed adjacent the upper end of the coil support 18 where it can

be moved into position in juxtaposition with the coil support 18 to band the coil 12 deposited thereon in a number of positions. In order to move the banded coil 12 a crane 22 carrying a suitable lifting device, for example, an electromagnet 24, is positioned adjacent the coil support 18, the crane 22 being disposed to be operated to move the lifting device 24 into engagement with the banded coil 12 to lift the coil 12 from the coil support 18 and deposit such banded coil in stock according to the width of the coil. A planned layout for the general assembly 10 of the apparatus referred to is shown generally in Fig. 2 and it is apparent that an efficient handling, banding and sorting of the coils 12 of different size can be readily obtained.

The turnstile assembly 14 is well known, being provided with a pivotally mounted supporting arm 26 for supporting a plurality of the slit strip coils 12 thereon and a hydraulically operated pusher 28 for applying a pushing force to the coils carried thereon to slide them

off of the arm 26 onto a suitable carrier. In this instance the turnstile assembly comprises two of the turnstile assemblies as better shown in Fig. 2 wherein slit strip coils can be unloaded from one of the turnstiles while the other turnstile is being loaded with a supply of the coils from a suitable source of supply or the mill represented by the outlined rectangle 29. The turnstile assemblies 14 are carried on a suitable carriage 30 mounted for movement on rails 32 so that the carriage 30 can be readily moved to position a loaded turnstile 14 in the unloading position while the unloaded turnstile 14 is in a position to receive another supply of the slit strip coils.

The coil carrying apparatus 16 in this instance is positioned in a pit 34 and extends upwardly therefrom being provided with a pivotally mounted rotatable arm 36 disposed to be moved into juxtaposition with a face of the end slit strip coil 12 carried on the turnstile assembly 14 when such turnstile is in an unloading position. In order to provide adequate support for the rotatable arm 36 when such arm carries a load, that is, one of the slit strip coils 12, the base of the coil carrying apparatus 16 is formed of a pair of upwardly extending side plates 38 and 40 which are secured to and are carried on a base member 42 in the pit 34, such side plates being further reinforced as by means of outwardly extending flange plates 44 secured at the outer edges of such side plates 38 and 40. While the flange plates 44 are shown in Figs. 1 and 3 through 6, they are omitted from the showing made in Fig. 7 for purposes of clarity. The side plates 38 and 40 project upwardly from the pit 34 a distance above the upper edge of the pit so that the arm 36 can be mounted therebetween adjacent the upper ends thereof for movement from an upwardly extending vertical position illustrated in Figs. 1 and 3 through a horizontal position illustrated in Fig. 4 to a downwardly depending vertical position illustrated in Fig. 5.

In mounting the rotatable arm 36 between the side plates 38 and 40, provision is made for actuating the arm 36. Thus, as more clearly shown in Figs. 6 and 7, the rotatable arm 36 comprises a pair of elongated side pieces 46 and 48 disposed in spaced relation to one another, the lower end of the side pieces 46 and 48 being angularly displaced so that the main or coil receiving portion of arm 36 will be offset with respect to its pivot support. The arm 36 is mounted on a shaft 50 which extends through the spaced side plates 38 and 40 at the upper end thereof. The shaft 50 is mounted for rotating movement in the side plates 38 and 40, suitable bearings being provided in aligned openings therein and flange type bearing members 52 and 54 being disposed on opposite sides of the side plates 38 and 40, respectively, for providing bearing surfaces for the shaft 50. Likewise a flange type bearing 56 and 58 is secured to the outer surface of the side pieces 46 and 48, respectively, of the arm 36 for bearing against suitable bushings 60 and 62, respectively, disposed between the bearing faces 52—56 and 54—58, respectively, of the assembly. In mounting the rotatable arm 36 on the shaft 50 a suitable pinion gear 64 is disposed between the side pieces 46 and 48 at the lower end thereof for receiving the shaft 50. The side pieces 46 and 48 and the pinion gear 64 are suitably keyed (not shown) to the shaft 50 for movement therewith so that when a force as described hereinafter is applied to the pinion gear 64 a rotatable movement of the arm 36 is obtained. A cam 66 is disposed on and suitably keyed to the shaft 50 in a manner not shown, the purpose of the cam 66 being described more fully hereafter.

In order to support one of the slit strip coils 12 on the rotatable arm 36 during a predetermined movement thereof, a rotatable pivotally mounted shoe support 70 is provided adjacent the upper end of the arm, the shoe support 70 being pivotally mounted as on a shaft 72 extending through suitable openings in the side pieces 46 and 48 of the arm 36. The shoe support 70 is pro-

vided with an outer curved surface 74 designed for receiving or fitting against the surface of the inner diameter of one of the wound slit strip coils 12. Such surface may be of metal or may be of one of the synthetic resinous products reinforced with fiber suitable for withstanding the frictional wear occasioned by engaging the inner surface of one of the coils. The shoe support 70 is of a length so that when the arm 36 is in the upwardly extending vertical position as illustrated in Figs. 1, 6 and 7, the outer end of the shoe 70 will project into and engage the inner surface of the end coil 12 as the end coil is moved from the arm 26 of the turnstile assembly 14. Thus when the arm 36 is in the upwardly extending vertical position the end of the shoe support 70 is in close proximity to the end of the arm 26 of the turnstile assembly 14 which carries the supply of slit strip coils 12.

In order to control movement of the shoe support 70 to the position illustrated in Figs. 6 and 7, the shoe 70 is connected as by means of links 76 and 78 to the end of a piston rod 80 of a hydraulically operated cylinder 82 which is carried between the side pieces 46 and 48. Thus, as illustrated, the link 78 is mounted on a pivot shaft 84 disposed to extend through suitable openings in the side pieces 46 and 48 and is pivotally connected at one point to the piston rod 80 and at another point to the end of link 76 which is connected to the shoe support 70. In order to support the hydraulic cylinder 82, its lower end is secured as by means of pivot connection 86 to a flange 88 carried by an I-beam 90 which is disposed between and secured to the side pieces 46 and 48. The hydraulic cylinder 82 may be any of the well known types and it is believed unnecessary to illustrate the details thereof since the structure and operation of such a cylinder is well known. Conduits 92 and 94 are connected to suitable ports (not shown) in the hydraulic cylinder 82 for supplying hydraulic pressure to the cylinder to actuate the piston rod 80 either upwardly to operate the linkage 76 and 78 in a manner to force the shoe support 70 to the position illustrated in Figs. 6 and 7 where it can support a coil 12, or downwardly to cause a collapse of the linkage 76 and 78 to move the shoe support 70 away from a supporting engagement with the coil 12 carried on the arm 36.

In order to actuate the rotatable arm 36, a segment gear 96 is mounted for rotatable movement on a shaft 98 disposed to extend through suitable openings in the side plates 38 and 40, such shaft being mounted and retained in position by means of a keeper plate 100, the gear segment 96 being disposed with the teeth thereof in engagement with the gear teeth of the pinion gear 64 as particularly illustrated in Figs. 3, 4 and 5. The segment gear 96 is provided with an outwardly extending flange 102 disposed to be positioned between the ends of a yoke 104, carried at the upper end of a piston rod 106, movement of which is controlled by a hydraulic cylinder 108. The flange 102 and yoke 104 are pivotally connected as by means of the shaft 110 extending therebetween and the lower end of the hydraulic cylinder 108 is mounted on a shaft 112 carried by a flange 114 on the base 42. The cylinder 108 may be of any of the well known types being provided with conduits 116 and 118 for supplying hydraulic pressure to the hydraulic piston (not shown) contained therein to control the upward or downward movement of the piston rod 106 and thereby control the rotating movement of the arm 36. The hydraulic pressure applied to the hydraulic cylinder 108 is preferably manually controlled by the operator of the apparatus, such control being of any of the well known types such as, for example, a multi-port valve which will be referred to hereinafter in connection with the operation of the hydraulic mechanism disposed for controlling the operation of the shoe support 70.

Again referring to Figs. 6 and 7, in order to control

the operation of the hydraulic cylinder 82 carried by the rotatable arm 36, a multi-port valve represented at 120 is secured in any suitable manner to the outer face of the side plate 38, the valve 120 being provided with a piston rod 122 as illustrated in Fig. 8 which carries a roller member 124, at its outer end disposed to be engaged by the cam 66 which is keyed to the shaft 50. The cam 66, as better shown in Fig. 6, is provided with three cam surfaces of predetermined size and length for operating the valve 120, representative details of which are schematically shown in Fig. 8, to any one of three positions depending upon the position of the arm 36, to control the hydraulic pressure applied to the hydraulic cylinder 82.

In assembling the hydraulic system for controlling the operation of the shoe support 70, the shaft 50 is drilled from each end inwardly thereof to points 126 and 128, indicated by dotted lines in Fig. 7, and the pinion gear 64 and shaft are drilled as indicated at 130 and 132 in dotted outline for providing passages from each of the ends of the shaft 50 which can be connected to the conduits 94 and 92, respectively, of the hydraulic cylinder 82. In order to connect the hydraulic system to the valve 120 the ends of each of the openings 126 and 128 drilled into the shaft 50 are connected as by means of rotating pipe joints 134 and 136, respectively, to be connected through conduits 138 and 140, respectively, to the valve 120. A suitable inlet conduit 142 is connected to a source of supply (not shown) of hydraulic pressure and a conduit 144 is disposed to be connected to exhaust the valve 120.

As illustrated in Fig. 8, the valve 120 is disposed to be actuated to a neutral position by the cam 66 when the cam surface 146 engages the roller 124 whereby equal pressures are applied to either side of the piston (not shown) of the hydraulic cylinder 82, and no movement of the shoe support 70 is effected. However, when the cam surface 148 engages the roller 124, the valve rod 122 is actuated downwardly to move each of the valves 150, 152 and 154 of the valve assembly 120 downwardly against the force of the spring 156, whereby port 158 is closed and hydraulic pressure is applied through the conduit 142, port 160, port 162, conduit 140, rotating pipe joint 134, conduit 136, drilled conduit 132 and conduit 92 to the lower end of the cylinder 82 to effect an upward movement of the piston rod 89 to operate the linkage 76 and 78 to effect a rotating movement of the shoe support 70 to the position illustrated in Figs. 6 and 7 where it extends outwardly in a substantially horizontal position from the arm 36. On the other hand, if the cam surface 164 engages the roller 124, the rod 122 is actuated upwardly as by means of the spring 156 to move the valves 150, 152 and 154 upwardly wherein port 160 is closed and hydraulic pressure is applied as through conduit 142, port 158, port 166, conduit 138, rotating pipe joint 134, the drilled opening 126, drilled opening 130 and conduit 94 to the upper end of the hydraulic cylinder 82 to effect a downward movement of the piston rod 89 to thereby collapse the linkage 76 and 78 and effect a pivotal movement of the shoe support 70 away from its outwardly extending position illustrated in Fig. 6, whereby the shoe support 70 will not engage the inner surface of the coil 12 carried on the rotatable arm 36.

As the rotatable arm 36 is pivotally moved away from the upwardly extending vertical position illustrated in Figs. 1, 3, 6 and 7 toward the horizontal position illustrated in Fig. 4, the shoe support 70 is actuated as last described to release the coil 12 carried thereby as the arm 36 approaches the horizontal position. In order to free the coil from the rotatable arm 36 and to support such coil in a manner where it can be suitably banded, the coil support 18 is disposed in the path of movement of the rotatable arm 36. In this instance the coil support 18 comprises a plurality of vertically extending and spaced posts 168 having coil receiving pads 169 on the

upper ends thereof, the posts 168 being carried in a suitable indexing mechanism 170. The indexing mechanism 170 in this instance is mounted for rotating movement about a shaft 172, better illustrated in Fig. 10, the lower end of the shaft being disposed to be mounted in suitable bushings 174 and 176 assembled in a housing 178 disposed to extend below the base 42 of the coil handling equipment. A suitable bearing flange 180 is carried by the shaft 172 for seating against the upper surface of the bushing 174 to limit downward movement of the shaft 172 in the assembly. In order to support the coil support posts 168 and the weight of a coil 12 when carried thereby, and also to provide for a free rotating movement of the indexing mechanism to effect a predetermined degree of indexing as will be described more fully hereinafter, a housing 182 is disposed over the upper end of the shaft 172 being mounted thereon as by means of suitable tapered roller bearing assemblies 184 and 186 at the upper and lower ends, respectively, of the housing 182, the roller bearing assemblies being so well known that they need not be further described herein. The housing 182 carries two spaced cam indexing plates 188 and 190 adjacent the upper end thereof, such plates 188 and 190 being suitably secured, as by welding, to the housing 182. Likewise a reinforcing plate 192 is carried by the lower end of the housing 182, being secured thereto as by welding. Each of the cam plates 188 and 190 and the reinforced plate 192 is provided with a series of five aligned openings therein disposed in predetermined spaced relation for receiving cylindrical pipe stanchions 194 therein, such stanchions being welded to each of the three plates and being of a size for receiving the lower end of a post 168. The upper end of each of the stanchions is grooved as at 196 for receiving a keying pin 198 disposed to extend through the posts 168.

As better illustrated in Fig. 9, the cam plates 188 and 190 are of a different size, the plate 188 being the smaller and having three cam surfaces 206, 208 and 204 terminating in pin receiving abutments 206, 208 and 210, respectively, whereas the cam plate 190 is larger and is provided with four cam surfaces 212, 214, 216 and 218 terminating in pin receiving abutments 220, 224, 226 and 228, respectively. The number of coil support posts 168 carried by the indexing mechanism 170 depends upon whether the coil is to be banded in three positions or in four positions. If the coil is to be banded in three positions, then three of the support posts 168 are disposed in and supported by pipe stanchions 194a, 194b and 194c corresponding to the three cam surfaces of the cam plate 188 and being approximately 120° apart. On the other hand, if the coil is to be banded in four positions, four of the support posts 168 are disposed in the cylindrical pipe stanchions 194a, 194d, 194e and 194c corresponding to the four cam surfaces of the cam plate 190 and being approximately 90° apart.

In order to effectively index the indexing equipment 170, a motor 230 having a suitable gear reducer is disposed to be connected through pivotally connected arms 232 and 234 to a rotatable pin 236 carried by an end of arm 234 and which is disposed to engage a cam surface of one of the cam plates 188 and 190, depending upon the positioning of the arm 234. Thus the arm 232 is connected through the gear reducer drive (not shown) to be driven in a clock-wise direction by the motor 230, a shaft 238 being carried at the outer end of such arm for supporting the arm 234. The shaft 238 extends through a suitable bushing 240 carried on the end of the arm 232 and is provided with an adjustable bushing flange 242 disposed to be secured to the shaft 238 in one of two positions depending upon the positioning of the arm 234 for positioning the pin 236 relative to a cam surface of one or the other of the cam plates 188 and 190. In order to insure that the pin 236 is biased against a cam surface of one of the cam plates 188 or 190, depending upon the positioning of the flange bushing 242, a spring, repre-

sented at 244 in Fig. 1, is disposed between a fixed collar 245 and the bearing end of arm 234 about the shaft 238 for providing friction loading between the collar 245 and the arm 234. Thus with the motor 230 operating clockwise and with the arm 234 spring loaded, the pin 236 is maintained in engagement with one of the cam surfaces of the selected cam plate 188 or 190.

In order to control the operation of the motor 230 so that the indexing apparatus 170 will not be operated except when the rotatable arm 36 is in the downwardly depending position, and will not interfere with movement of the coil support post 168, a movable contact member 246 is mounted between the side plates 36 and 40. The movable contact member 246 is disposed to be engaged by the rotatable arm 36 only when the rotatable arm 36 is in the downwardly depending vertical position whereby the contact member 246 is moved to a circuit establishing position where it bridges fixed contact members 248 to establish an energizing circuit through contact member 249 (shown in its circuit interrupting position) to a suitable source of power (not shown) for the motor 230. Thus, after the operator has actuated contact member 249 to its circuit closing position the operation of the motor 230 is automatically controlled by the operation of contact member 246 and is interrupted by movement of contact member 249 to the circuit interrupting position or by movement of the arm 36 to release contact member 246.

In operation, when the turnstile assembly 14 is provided with a supply of the slit strip coils 12 and is moved to an unloading position and the crane 22 is operated to move the lifting device 24 out of the path of movement of rotatable arm 36, the operator of the apparatus supplies hydraulic pressure as through the conduit 118 to the hydraulic cylinder 108 to actuate the segment gear 96 which is in engagement with the pinion gear 64 to effect a clock-wise movement of the rotatable arm 36 from the downwardly depending position through the horizontally extending position to the upwardly extending vertical position illustrated in Fig. 1. As the rotatable arm 36 moves from the downwardly depending vertical position illustrated in Fig. 5, the contact member 246 is moved to a circuit interrupting position whereby the motor 230 cannot be energized to actuate the coil support and indexing apparatus 18. As the rotatable arm 36 moves through the horizontal position illustrated in Fig. 4, the cam surface 164 of cam 66 still engages the roller 124 with the result that the hydraulic pressure supplied to the hydraulic cylinder 82 is not changed. As the rotatable arm moves from the horizontal position toward the upwardly extending vertical position, cam surface 146 engages the roller 124 to place the multi-port valve 120 in its neutral operating position whereby the hydraulic cylinder 82 is still not operating to effect an operation of the shoe support 70. As the rotatable arm 36 approaches the upwardly extending substantially vertical position illustrated in Fig. 1, the cam surface 148 of cam 66 engages the roller 124 and effects an operation of the valve 120 to admit hydraulic pressure as described hereinbefore to the cylinder 82 to effect an operation of the shoe support 70 to its outwardly extending position. However, because of the time delay inherent in the operation of a hydraulic system of the type utilized and described herein, it is found that the shoe support 70 will not actually be actuated into engagement with the inner surface of a coil until after the rotatable arm 36 is actually in the upwardly extending vertical position. Thus an operator can effectively move the first slit strip coil 12 on the arm 26 of the turnstile 14 towards the vertical arm 36 so that the coil overhangs the end of the arm 26 a measurable distance before the shoe support 70 actually engages the inner surface of such end coil. This time delay saves wear and tear on the surface of the shoe support 70 and also makes it impossible for the shoe support to be out of alignment with the end of the arm 26 when the end coil is moved therefrom.

With the rotatable arm 36 in the upwardly extending vertical position illustrated in Figs. 1 and 3, the operator effects an operation of the hydraulic pusher rod 28 to move the end slit strip coil 12 toward the face of the rotatable arm 36 to a position where the inner surface of the coil is engaged by the shoe support 70 which functions to support and maintain the coil in position on the rotatable arm 36. The operator then effects an operation of the control valve (not shown) for the hydraulic cylinder 108 to effect a downward movement of the piston rod 106 to actuate the segment gear 96 in a clock-wise direction to effect a counterclockwise movement of the pinion gear 64 to move the rotatable arm toward the horizontal position illustrated in Fig. 4. As the rotatable arm 36 leaves the upwardly extending vertical position, the cam 66 is driven so that the roller 124 of control valve 120 moves from the cam surface 148 to the cam surface 146, thereby effecting an operation of the control valve 120 to a neutral position whereby movement of the shoe support 70 is prevented. As the rotatable arm 36 approaches the horizontal position of Fig. 4, the roller 124 rolls from the cam surface 146 of cam 66 to the cam surface 164, whereby the control valve 120 is actuated to permit a flow of the hydraulic fluid through the conduit 138, rotating pipe joint 134, shaft 50 and conduit 94 to effect an operation of the hydraulic cylinder 82 to collapse the linkage 78 and cause a movement of the shoe support 70 away from its contact engagement with the coil carried on the rotatable arm 36.

Assuming that the coil 12 carried by the rotatable arm 36 is to be banded in four positions, then four of the coil support posts 168 are positioned in and carried by the cylindrical stanchions 194a, 194d, 194e and 194c of the indexing support mechanism 170. Two of the posts 168 are thus spaced on opposite sides of the path of movement of the rotatable arm 36 so that the arm 36 will move downwardly in the space provided therebetween. Thus, as the arm 36 approaches the horizontal position, the overlapping edges of the coil 12 carried thereon are brought into engagement with the pads 169 carried on the upper ends of the posts 168 on opposite sides of the arm 36, whereby the coil is supported in a substantially horizontal position on the upper ends of the posts 168 and the arm 36 is free to continue its rotation to a downwardly extending vertical position as represented in Fig. 5. It is necessary that the rotatable arm 36 complete its downward movement to the downwardly extending vertical position in order to clear the space between the spaced support posts 168 whereby the support posts 168 may be indexed through a plurality of banding positions.

With the coil carried on the pads 169 of the spaced support posts 168, a suitable banding machine represented by the rectangle 20 is moved to a position where a band (not shown) may be passed about the coil for banding the coil. Upon completion of the movement of the rotatable arm 36 to the downwardly extending vertical position, the contact member 246 is actuated by the arm 36 to a circuit closing position whereby the operator, by operating contact member 249, can effect an operation of the motor 230. Since the motor 230 is connected through arm 232 and the friction loaded arm 234 to position the pin 236 on one of the cam surfaces of the cam plate 190, operation of the motor 230 will effect movement of the pin 236 along said cam surface to a position where the pin 236 engages the pin receiving abutment associated with such cam surface whereby further operation of the motor 230 and a rotation of the arm 232 will apply a pulling force directly to the cam plate 190 to index the cam plate 190 forward one-quarter of a turn before the pin 236 is released from the pin receiving abutment and rolls back over such cam surface to engage the next succeeding cam surface and position itself in the pin receiving abutment associated with such succeeding cam surface. The indexing of the coil support is controlled by an operator so that as much time can be taken in each

banding position as is necessary to effect a successful banding of the coil in such position.

If instead of banding the coil in four positions it is desired to band the coil in three positions, then three of the support posts 168 are positioned in the cylindrical stanchions 194a, 194b and 194c and the posts are removed from the cylindrical stanchions 194d and 194e. As will be appreciated, the rotatable arm 36 will still move between certain of the spaced posts 168 to deposit the coil on the upper ends of such posts. However, in this instance, in order to index the support mechanism 120° instead of the 90° as in the previous case, the fixed bushing 242 is moved upwardly along the shaft 238 to position the arm 234 in alignment with the cam plate 188 whereby the pin 236 is maintained in engagement with one of the cam surfaces of such cam plate and will seat in the pin receiving abutment associated with such cam surface when the motor 230 is operated to effect a movement of the cam plate 188 through an angle of 120°.

As soon as the coil is banded in a predetermined number of positions, the crane 22 is operated to move the lifting device 24 into engagement with the banded coil and the banded coil is removed from the posts 168 and stored with other coils of the same size. Thereafter the operator will effect an operation of the control valve (not shown) which controls the hydraulic pressure applied to the hydraulic cylinder 108 to effect an upward movement of the piston rod 106 and thereby effect a counterclockwise movement of the segment gear 96 to effect a clockwise movement of the pinion gear 64 and thereby drive the rotatable arm 36 from its downwardly extending vertical position illustrated in Fig. 5 upwardly between the spaced coil support posts 168 through the horizontal position illustrated in Fig. 4 to the upwardly extending vertical position illustrated in Fig. 3 to the position where the shoe support 70 is actuated upwardly as described hereinbefore to again engage the inner surface of the succeeding end slit strip coil as it is pushed from the arm 26 of the turnstile assembly.

As is evident from the foregoing description, apparatus is provided for the efficient mechanical handling of a slit strip coil whereby the slit strip coil can be readily moved from a vertical position to a horizontal position where it can be readily banded and then moved to stock, the apparatus providing an efficient handling of the coil through a predetermined number of banding positions. In addition, safety features are provided for insuring that the coil support in the banding position cannot be operated until the coil-moving arm is free of the coil support. With the apparatus described, it has been found that there is little if any damage to the coil during the movement and handling thereof in effecting the banding of the coil. The apparatus is compact and integrated and takes very little room from the mill floor. Further, the use of manpower in handling a coil for banding can be decreased to one operator who can efficiently operate the discharge of the coil from the turnstile and the rotating operation of the rotatable arm, as well as the indexing apparatus for the coil support when the coil is in the banding position. The apparatus described and claimed can be constructed of substantially standard component parts and can be readily reproduced by anyone skilled in the art.

I claim:

1. In apparatus for handling strip coils to facilitate the banding thereof, the combination comprising, arm means for carrying a supply of slit strip coils with their faces in substantially vertical parallel relation, a rotatable arm disposed for movement between an upwardly extending vertical position and a horizontal position, means for effecting movement of the rotatable arm between the vertical position and the horizontal position, a shoe support pivotally carried by the rotatable arm, means actuated by movement of the rotatable arm to the upwardly extending vertical position to effect pivotal movement of the

shoe support to extend outwardly therefrom in alignment with the coil carrying arm means to receive the end slit strip coil therefrom and to maintain said end coil in supported relation on the rotatable arm, said shoe support actuating means also being disposed to be actuated by movement of the rotatable arm to the horizontal position to effect pivotal movement of the shoe support to release the slit strip coil when the rotatable arm is in the horizontal position, and a coil support member disposed to receive the slit strip coil when the rotatable arm is in the horizontal position to thereby free the slit strip coil from the rotatable arm.

2. In apparatus for handling strip coils to facilitate the banding thereof, the combination comprising, arm means for carrying a supply of slit strip coils with their faces in substantially vertical parallel relation, a rotatable arm disposed for movement between an upwardly extending vertical position and a horizontal position, means for effecting movement of the rotatable arm between the vertical and horizontal positions, a shoe support pivotally carried by the rotatable arm, hydraulic means carried by the rotatable arm and connected to the pivotally mounted shoe support for controlling the pivotal movement thereof, valve means responsive to movement of the rotatable arm disposed to control the operation of the hydraulic means, the hydraulic means being disposed when the rotatable arm is actuated to the vertical position to effect pivotal movement of the shoe support to extend outwardly therefrom in alignment with the coil carrying arm means to receive the end slit strip coil therefrom and to maintain said end coil in supported relation on the rotatable arm, the hydraulic means also being disposed when the rotatable arm moves from the vertical position to the horizontal position to effect pivotal movement of the shoe support to release the slit strip coil when the rotatable arm is in the horizontal position, and a coil support member disposed adjacent the path of movement of the rotatable arm to receive the slit strip coil when the rotatable arm is in the horizontal position to thereby free the slit strip coil from the rotatable arm.

3. In apparatus for facilitating the banding of strip coils, the combination comprising, arm means for carrying a supply of slit strip coils with their faces in substantially vertical parallel relation, a rotatable arm disposed for movement from a downwardly depending vertical position through a horizontal position to an upwardly extending vertical position, means for effecting movement of the rotatable arm from one of said vertical positions to the other of said vertical positions, a shoe support pivotally carried by the rotatable arm, means actuated by movement of the rotatable arm to the upwardly extending position to effect pivotal movement of the shoe support to extend outwardly therefrom toward and in alignment with the coil carrying arm means to receive the end slit strip coil therefrom and to maintain said end coil in supported relation on the rotatable arm, a plurality of upwardly extending coil receiving support members disposed adjacent to the rotatable arm, said coil receiving support members being spaced from one another to permit passage of the rotatable arm between certain of the support members during a movement of the rotatable arm from one of said vertical positions to the other of said vertical positions, the upper ends of the spaced support members being disposed to seat against a face of the strip coil carried by the rotatable arm as the rotatable arm is moved through its horizontal position from the upwardly extending to the downwardly depending vertical position to thereby free the strip coil from the rotatable arm and support the strip coil with its faces in a substantially horizontal parallel relation in a band receiving position, and means for indexing the spaced support members and the strip coil supported thereby in a predetermined manner when the rotatable arm is in its downwardly depending vertical position to progressively move the strip coil through a predetermined number of band receiving positions.

11

4. In apparatus for facilitating the banding of strip coils, the combination comprising, arm means for carrying a supply of slit strip coils with their faces in substantially vertical parallel relation, a rotatable arm disposed for movement from a downwardly depending vertical position through a horizontal position to an upwardly extending vertical position, means for effecting movement of the rotatable arm from one of said vertical positions to the other of said vertical positions, a shoe support pivotally carried by the rotatable arm, means actuated by movement of the rotatable arm to the upwardly extending position to effect pivotal movement of the shoe support to extend outwardly therefrom toward and in alignment with the coil carrying arm means to receive the end slit strip coil therefrom and to maintain said end coil in supported relation on the rotatable arm, a plurality of upwardly extending coil receiving support members disposed adjacent to the rotatable arm, said coil receiving support members being spaced from one another to permit passage of the rotatable arm between certain of the support members during a movement of the rotatable arm from one of said vertical positions to the other of said vertical positions, said shoe support actuating means being actuated by movement of the rotatable arm to the horizontal position to effect pivotal movement of the shoe support away from the strip coil carried by the rotatable arm to release the strip coil when the rotatable arm is in the horizontal position, the upper ends of the spaced support members being disposed to seat against a face of the strip coil carried by the rotatable arm when the rotatable arm is moved through its horizontal position from the upwardly extending to the downwardly depending vertical position to thereby free the strip coil from the rotatable arm and support the strip coil with its faces in a substantially horizontal parallel relation in a band receiving position, and means for indexing the spaced support members and the strip coil supported thereby in a predetermined manner when the rotatable arm is in its downwardly depending vertical position to progressively move the strip coil through a predetermined number of band receiving positions.

5. In apparatus for facilitating the banding of strip coils, the combination comprising, arm means for carrying a supply of slit strip coils with their faces in substantially vertical parallel relation, a rotatable arm disposed for movement from a downwardly depending vertical position through a horizontal position to an upwardly extending vertical position, means for effecting movement of the rotatable arm from one of said vertical positions to the other of said vertical positions, a shoe support pivotally carried by the rotatable arm, means actuated by movement of the rotatable arm to the upwardly extending position to effect pivotal movement of the shoe support to extend outwardly therefrom toward and in alignment with the coil carrying arm means to receive the end slit strip coil therefrom and to maintain said end coil in supported relation on the rotatable arm and to effect pivotal movement of the shoe support when the rotatable arm moves therefrom to the horizontal position to release the strip coil when the rotatable arm is in the horizontal position, a plurality of upwardly extending coil receiving support members disposed adjacent to the rotatable arm, said coil receiving support members being spaced from one another to permit passage of the rotatable arm between certain of the support members during a movement of the rotatable arm from one of said vertical positions to the other of said vertical positions, the upper ends of the spaced support members being disposed to receive and seat against a face of the strip coil carried by the rotatable arm when the rotatable arm is moved through its horizontal position from the upwardly extending to the downwardly depending vertical positions to thereby remove the strip coil from the spaced support members to permit movement of the rotatable arm from the downwardly depending vertical position to the upwardly extending vertical position in a substantially horizontal parallel relation in a band receiving position, and means for indexing the spaced support members and the strip coil supported thereby in a predetermined manner to progressively move the strip coil through a predetermined number of band receiving positions.

12

receiving position, means disposed for operation to index the spaced support members and the strip coil supported thereby in a predetermined manner to progressively move the strip coil through a predetermined number of band receiving positions, and means disposed to be actuated when the rotatable arm is in the downwardly depending vertical position to insure the operation of the indexing means only when the rotatable arm is in said downwardly depending vertical position.

6. In apparatus for facilitating the banding of strip coils, the combination comprising, arm means for carrying a supply of slit strip coils with their faces in substantially vertical parallel relation, a rotatable arm disposed for movement from a downwardly depending vertical position through a horizontal position to an upwardly extending vertical position, means for effecting movement of the rotatable arm from one of said vertical positions to the other of said vertical positions, a rotatable shoe support pivotally carried by the rotatable arm, means actuated by movement of the rotatable arm to the upwardly extending position to effect pivotal movement of the shoe support to extend outwardly therefrom toward and in alignment with the coil carrying arm means to receive the end slit strip coil therefrom and to maintain said end coil in supported relation on the rotatable arm and to effect pivotal movement of the shoe support when the rotatable arm moves therefrom to the horizontal position to release the strip coil when the rotatable arm is in the horizontal position, a plurality of upwardly extending coil receiving support members disposed adjacent to the rotatable arm, said coil receiving support members being spaced from one another to permit passage of the rotatable arm between certain of the support members during a movement of the rotatable arm from one of said vertical positions to the other of said vertical positions, the upper ends of the spaced support members being disposed to receive and seat against a face of the strip coil carried by the rotatable arm when the rotatable arm is moved through its horizontal position from the upwardly extending to the downwardly depending vertical positions to thereby remove the coil from the rotatable arm and support the strip coil with its faces in a substantially horizontal parallel relation in a band receiving position, means disposed for operation to rotatably index the spaced support members and the strip coil supported thereby in a predetermined manner to progressively move the strip coil through a predetermined number of band receiving positions, means disposed to be actuated when the rotatable arm is in the downwardly depending vertical position to insure the operation of the indexing means only when the rotatable arm is in said downwardly depending vertical position, and means for removing the banded strip coil from the spaced support members to permit movement of the rotatable arm from the downwardly depending vertical position to the upwardly extending vertical position.

7. In apparatus for facilitating the banding of strip coils, the combination comprising, arm means for carrying a supply of slit strip coils with their faces in substantially vertical parallel relation, a rotatable arm disposed for movement from a downwardly depending vertical position through a horizontal position to an upwardly extending vertical position, means for effecting movement of the rotatable arm from one of said vertical positions to the other of said vertical positions, a shoe support pivotally carried by the rotatable arm and connected to the pivotally mounted shoe support for controlling the pivotal movement thereof, valve means responsive to movement of the rotatable arm disposed to control the operation of the hydraulic means, the hydraulic means being disposed when the rotatable arm is in the upwardly extending vertical position to effect pivotal movement of the shoe support to extend outwardly therefrom toward and in alignment with the coil carrying arm means to receive the end slit strip coil therefrom and to maintain said end

coil in supported relation on the rotatable arm and to effect pivotal movement of the shoe support when the rotatable arm moves therefrom to the horizontal position to release the strip coil when the rotatable arm is in the horizontal position, a plurality of upwardly extending coil receiving support members disposed adjacent to the rotatable arm, said coil receiving support members being spaced from one another to permit passage of the rotatable arm between certain of the support members during a movement of the rotatable arm from one of said vertical positions to the other of said vertical positions, the upper ends of the spaced support members being disposed to receive and seat against a face of the strip coil carried by the rotatable arm when the rotatable arm is moved through its horizontal position from the upwardly extending to the downwardly depending vertical position to thereby remove the coil from the rotatable arm and support the strip coil with its faces in a substantially horizontal parallel relation in a band receiving position, and means disposed for operation to rotatably index the spaced support members and the strip coil supported thereby in a predetermined manner when the rotatable arm is in its downwardly depending vertical position to progressively move the strip coil through a predetermined number of band receiving positions.

8. In apparatus for facilitating the banding of strip coils, the combination comprising, means for supporting a supply of slit strip coils in side by side relation with their faces in substantially vertical parallel relation, a pivotally mounted arm disposed to be rotated from a downwardly depending vertical position through a horizontal position to an upwardly extending vertical position, means for effecting movement of the pivotally mounted arm from one of said vertical positions to the other of said vertical positions, a shoe support pivotally carried by the arm, hydraulic means carried by the arm for movement therewith and connected to the pivotally mounted shoe support for controlling the pivotal movement thereof, valve means connected to the hydraulic means for controlling the operation thereof, means responsive to the pivotal movement of the arm for controlling the operation of the valve means to effect an operation of the hydraulic means to move the shoe support to a position perpendicular to the arm and in alignment with the coil supply supporting means when the arm is in the upwardly extending vertical position to receive the end coil thereon and maintain said end coil in supported relation on the arm and to retract the shoe support from said position perpendicular to the arm when the arm moves to the horizontal position to thereby release said end coil, and spaced coil receiving support members disposed adjacent the path of movement of the arm for receiving and supporting the coil in a banding position as the arm moves from the horizontal position to the downwardly depending vertical position.

9. In apparatus for facilitating the banding of strip coils, the combination comprising, means for supporting a supply of slit strip coils in side by side relation with their faces in substantially vertical parallel relation, a pivotally mounted arm disposed to be rotated from a downwardly depending vertical position through a horizontal position to an upwardly extending vertical position, means for effecting movement of the pivotally mounted arm from one of said vertical positions to the other of said vertical positions, a shoe support pivotally carried by the arm, hydraulic means carried by the arm for movement therewith and connected to the pivotally mounted shoe support for controlling the pivotal movement thereof, valve means connected to the hydraulic means for controlling the operation thereof, means responsive to the pivotal movement of the arm for controlling the operation of the valve means to effect an operation of the hydraulic means to move the shoe support to a position perpendicular to the arm and in alignment with the coil supply supporting means when the

arm is in the upwardly extending vertical position to receive the end coil thereon and maintain said end coil in supported relation on the arm and to retract the shoe support from said position perpendicular to the arm when the arm moves to the horizontal position to thereby release said end coil, a plurality of upwardly extending coil receiving support members disposed in spaced relation to one another adjacent the path of movement of the arm to permit passage of the arm between certain of the support members as the arm moves from one of said vertical positions to the other of said vertical positions, said spaced support members being disposed to receive and support the coil in a banding position as the arm moves from the horizontal to the downwardly depending vertical position, and means disposed for operation to rotatably index the spaced support members and the strip coil supported thereon in a predetermined manner when the arm is in its downwardly depending vertical position to progressively index the strip coil through a predetermined number of banding positions.

10. In apparatus for facilitating the banding of strip coils, the combination comprising, means for supporting a supply of slit strip coils in side by side relation with their faces in substantially vertical parallel relation, a pivotally mounted arm disposed to be rotated from a downwardly depending vertical position through a horizontal position to an upwardly extending vertical position, means for effecting movement of the pivotally mounted arm from one of said vertical positions to the other of said vertical positions, a shoe support pivotally carried by the arm, hydraulic means carried by the arm for movement therewith and connected to the pivotally mounted shoe support for controlling the pivotal movement thereof, valve means connected to the hydraulic means for controlling the operation thereof, means responsive to the pivotal movement of the arm for controlling the operation of the valve means to effect an operation of the hydraulic means to move the shoe support to a position perpendicular to the arm and in alignment with the coil supply supporting means when the arm is in the upwardly extending vertical position to receive the end coil thereon and maintain said end coil in supported relation on the arm and to retract the shoe support from said position perpendicular to the arm when the arm moves to the horizontal position to thereby release said end coil, a plurality of upwardly extending coil receiving support members disposed in spaced relation to one another adjacent the path of movement of the arm to permit passage of the arm between certain of the support members as the arm moves from one of said vertical positions to the other of said vertical positions, said spaced support members being disposed to receive and support the coil in a banding position as the arm moves from the horizontal to the downwardly depending vertical position, and means disposed for operation to rotatably index the spaced support members to progressively index the strip coil supported thereon through a predetermined number of banding positions, and means responsive to the positioning of the arm in the downwardly depending vertical position for permitting operation of the indexing means only while the arm is in the downwardly depending vertical position.

11. In apparatus for handling strip coils from a supply carried by an arm to facilitate the banding of the coils, the combination comprising, a rotatable arm disposed for movement between an upwardly extending vertical position and a horizontal position, means for effecting movement of the rotatable arm between said positions, a shoe support pivotally carried by the rotatable arm and disposed for movement to extend outwardly therefrom in substantial alignment with the supply arm to receive a coil from said supply when the rotatable arm is in the upwardly extending vertical position, operative means actuated by movement of the rotatable arm to the upwardly extending vertical position disposed to effect

a pivotal movement of the shoe support to said outwardly extending position to receive a coil from the supply arm, said operative means also being disposed to be actuated by movement of the rotatable arm from the upwardly extending vertical position to the horizontal position to effect pivotal movement of the shoe support away from said outwardly extending position to release the coil as the rotatable arm approaches the horizontal position, and a coil support member disposed adjacent the path of movement of the rotatable arm to receive the coil 10 when the rotatable arm is in the horizontal position to thereby free the coil from the rotatable arm.

12. In apparatus for handling strip coils from a supply carried by an arm to facilitate the banding of the coils, the combination comprising, a rotatable arm disposed 15 for movement between an upwardly extending vertical position and a horizontal position, means for effecting movement of the rotatable arm between said positions, a shoe support pivotally carried by the rotatable arm and disposed for movement to extend outwardly therefrom in substantial alignment with the supply arm to receive a coil from said supply when the rotatable arm is in the upwardly extending vertical position, hydraulic means carried by the rotatable arm and connected to the pivotally mounted shoe support for controlling the pivotal 25

movement thereof, valve means disposed to be operated to control the operation of the hydraulic means, cam means disposed for movement with the rotatable arm and connected to control the operation of the valve means, 5 the cam means being disposed when the rotatable arm approaches the upwardly extending vertical position to operate the valve to initiate an operation of the hydraulic means to effect pivotal movement of the shoe support to said outwardly extending position to receive a coil from the supply arm, the cam means also being disposed when the rotatable arm approaches the horizontal position to operate the valve to initiate an operation of the hydraulic means to effect a pivotal movement of the shoe support away from said outwardly extending position to release the coil carried by the rotatable arm, and a coil support member disposed adjacent the path of movement of the rotatable arm to receive the coil when the rotatable arm is in the horizontal position to thereby free the coil from the rotatable arm.
